DOOR LATCH MECHANISM

William C. Devereaux, Detroit, Mich.

Application December 5, 1932, Serial No. 645,847

13 Claims. (Cl. 292—169)

This invention relates generally to door latch mechanism, especially vehicle door latch mechanism, and consists of certain novel features of construction, combinations and arrangements of parts, that will be hereinafter more fully described and particularly pointed out in the appended claims.

In the accompanying drawings:

Figure 1 is a fragmentary vertical sectional view of a door with latch mechanism embodying my invention applied thereto;

Figure 2 is a horizontal sectional view taken on the line 2—2 of Figure 1;

Figure 3 is a sectional view taken on the line 3—3 of Figure 2;

Figure 3A is a detail view of the rollback;

Figure 4 is a front elevation of the door latch mechanism;

Figure 4A is a detail view of the spring washer;

Figure 5 is a side elevation of a slightly modified latch construction;

Figure 6 is a top plan view of the construction illustrated in Figure 5;

Figure 7 is a front elevation of the construction illustrated in Figure 5;

Figure 8 is a detail view of the inside handle stem illustrated in Figures 5 to 7, inclusive;

Figure 9 is an end elevation of the stem illustrated in Figure 8;

Figure 10 is a detail view of the rivet illustrated in Figure 6;

Figure 11 is a detail view of the inside rollback illustrated in Figure 5;

Figure 12 is a detail view of the spring washer used in the modification;

Figure 13 is a detail view of the rollback used in the modification;

Figure 14 is a plan view of the spring;

Figure 15 is a side elevation thereof.

Figure 16 is a fragmentary horizontal sectional view through the handle assembly with parts broken away and in section.

Referring now to the drawings, A is a vehicle door; B is a vertically movable glass panel in said door, and C is a runway for said glass panel. D is a latch case plate having portions 1 and 2 respectively secured to opposite sides of the door and having an intermediate transversely extending portion 3 at the forward edges of said portions secured to the free edge of the door. E is a latch bolt extending through an opening in the transversely extending portion 3 for engagement with a suitable keeper (not shown) and having a shank 4 slidably mounted on the inner portion 1 of the case plate, and F is a spring anchored on the in-

ner portion 1 of the case plate and having an arm 5 engaging a lateral flange 6 of the shank and normally holding the bolt E in projected position. G is a cover plate arranged in spaced relation to the outer portion 2 of the case plate and rigidly secured thereto; H is a handle operable from the outer side of the door and having a stem 7 of substantially square cross section disposed substantially parallel to the transversely extending portion 3 of the case plate and received in aligned openings in the outer portion 2 of the case plate and cover plate G, and I is a rollback on the stem 7 between the cover plate G and outer portion 2 and having an upstanding arm 10. Preferably this rollback I is provided at diametrically opposite points thereof with notches 11 and 12 that receive lateral lugs 13 and 14 respectively of a spring washer J on the stem 7 corresponding to that set forth in my application filed October 10, 1932 and bearing Serial Number 637,175.

In the present instance, the rollback I upon the outer portion 2 of the case plate effects a retraction of the bolt E upon the inner portion 1 of the case plate by means of an intermediate yoke or actuator K which straddles the runway C for the glass panel B. As shown, the base 15 of this yoke is movable vertically in a suitable opening 16 in the transversely extending portion 3 of the case plate while the sides 17 and 18, respectively, thereof are pivoted upon suitable studs 19 or rivets 19 and 20, respectively, extending transversely of the inner and outer portions 1 and 2 of the case plate. The outer side 18 has a depending arm 21 in rear of and adapted to be engaged by the arm 10 of the rollback, while the inner side 17 has a depending arm 22 in advance of and adapted to engage a lateral flange 23 of the bolt shank. Thus by operating the outside handle H to turn the rollback I clockwise against the arm 21 of the yoke, the latter will swing 40 downwardly about the rivets 19 and 20 so that the arm 22 will be moved anti-clockwise against the flange 23 of the bolt shank. As a result the latch bolt E will be retracted against the tension of the spring F.

For dogging or rendering the outside rollback I inoperative I have provided a rollback M which is pivoted upon the inner portion 1 of the case plate and has a downwardly extending arm 24 engageable with a recess 25 in the inner side 17 of the yoke. As shown, this rollback M has a hub 26 mounted to turn in aligned openings in the inner portion 1 of the case plate and in a suitable cover plate O upon said inner portion and is adapted to be turned by a laterally projecting

stem R and handle T upon the inner side of the door. Preferably this arm 24 of the rollback is in advance of and is engageable with a lateral flange 29 of the bolt shank to effect the retraction of the bolt. A second arm 30 extends downwardly from the rollback M so as to be in the path of the lateral flange 29 of the bolt shank when the arm 24 is in dogging engagement with the yoke. Thus by turning the inside rollback M clockwise the arm 10 24 thereof will be engaged with the recess 25 and will cause the yoke D and outside rollback I to be dogged. Any suitable means such as the spring X carried by the cover plate O may be used to detachably hold the rollback M in such 15 dogging position. By turning the inside rollback M anti-clockwise the arm 24 will engage the lateral flange 29 of the bolt shank and will cause the bolt E to be retracted against the tension of the spring F. Normally the arm 24 is held by the 20 spring X in engagement with the lateral flange 29 of the bolt shank. However, should the arm 24 be in the dogged position, i. e., in the recess 25 in the yoke when the door is open, the lateral flange 29 of the bolt shank will engage and swing 25 the arm 30 of the rollback in an anti-clockwise direction when the door is subsequently closed or slammed shut. As a result the arm 24 will be moved out of the recess 25 in the yoke and the latter may then be moved by the outside handle H to effect a retraction of the bolt. Thus this 30 feature prevents the possibility of the driver being locked outside the car if the rollback M is not in normal position when the door is moved from open to closed position.

35 In Figures 5 to 15 inclusive, I have illustrated a slight modification wherein 40 is a latch case plate secured upon the inner side of the door and provided at its forward edge with a lateral flange 41 that is secured to the forward edge of the door. 40 is a latch bolt extending through an opening in the lateral flange 41 for engagement with a suitable keeper (not shown) and having a rearwardly extending shank 43 fixed thereto and disposed substantially parallel to the case plate, and 45 44 is a spring anchored on the case plate and having an arm 45 between the case plate and shank 43 engaging the rear end of the bolt and normally holding the same in projected position. 46 is a cover plate parallel and secured to the case plate 40; 47 is a handle operable from the outer side of the door and having a stem 48 of substantially square cross section disposed substantially parallel to the lateral flange 41 and received in aligned openings in the case plate 40 and cover plate 46, and 49 is a rollback sleeved on the stem 48 between the plates 40 and 46 and having an upstanding arm 50 engageable with a lateral flange 51 of the bolt shank to effect a retraction of the bolt. Any suitable means such as the lugs 52 struck out from the case plate 40 may be used 55 as abutments for the rollback arm 50 to limit the forward swinging movement thereof, while any suitable means such as the spring washer 53 sleeved on the stem 48 and having diametrically opposed struck-out lugs 54 and 55 respectively engaging diametrically opposed notches 56 and 57 respectively in the rollback may be employed to take up play between the stem 48 and rollback 49 and maintain the parts in proper assembled relation.

58 is a handle operable from the inner side of a door and having a stem 59 journaled in the case plate 40. 60 is a rivet having a head 61 upon the inner side of the bolt shank 43, having a circular portion 62 within an elongated slot 63 in the

shank 43, and having a spirally knurled shank 64 engaging an axial socket 65 in the inner end of the stem 59. 66 is a rollback non-rotatably sleeved on the stem 59 between the shank 43 and case plate 40 and having an upstanding arm 67 provided with a rounded portion 68 for engagement with a lateral flange 69 of the shank 43 for effecting a retraction of the bolt, provided with a shoulder 70 for engagement with a rearwardly extending arm 71 of the outside rollback to dog 10 the latter and render the outside handle 47 inoperative, and having an offset end portion 72 engageable by the lateral flange 51 of the shank when the latter is moved rearwardly by pressure applied directly upon the outer end of the bolt 42 15 as when the door is moved to closed position or is blown or slammed shut. Thus with this construction the rivet 60 forms a guide for the bolt shank 43 and cooperates with said shank to hold the handle stem 59 in proper assembled position 20 in the case plate and to hold the rollback 66 in proper assembled position upon said stem.

In use, the bolt 42 may be retracted against the tension of the spring 44 by moving the outside rollback 49 clockwise against the flange 51, or 25 by moving the inside rollback 66 clockwise against the lateral flange 69. When the bolt 42 is in projected position and the outside rollback arm 50 is in engagement with the lugs 52, the inside rollback 66 may be turned anticlockwise 30 so that the shoulder 70 may engage the arm 71 of the outside rollback. The outside rollback will then be dogged and rendered inoperative. Any suitable means such as the spring leaf or washer 80 on the stem 59 between the case plate 40 and 35 the rollback 66 may be used to detachably hold the said rollback in this dogged position. The outside rollback 49 may be readily released by moving the inside rollback 66 clockwise to disengage the shoulder 70 from the arm 71. Normally the arm 67 is held by the spring 80 in engagement with the lateral flange 69 of the bolt shank. However, should the outside rollback 49 be dogged by the shoulder 70 of the inside roll- 40 back when the door is open, the lateral flange 51 of the bolt shank will engage and swing the offset end portion 72 of the arm 67 in an anti-clockwise direction when the door is subsequently closed or slammed shut. As a result the 45 shoulder 70 of the inside rollback 66 will be disengaged from the arm 71 of the outside rollback and the latter may then be moved by the outside handle 47 to effect a retraction of the bolt. Thus 50 this feature prevents the possibility of the driver being locked outside the car if the rollback 66 is not in normal position when the door is moved from open to closed position.

What I claim as my invention is:

1. In a door latch, a latch bolt having a shank, a rollback engageable with one portion of the shank to move the bolt, and a second rollback engageable with another portion of the shank to move the bolt, engageable with the first rollback to dog the same, and actuatable by one of the portions aforesaid of the shank to release the first mentioned rollback.
2. In a door latch mechanism, a latch bolt having two lateral projections, means engageable with one of said projections for retracting the bolt, and means engageable with the second projection to effect a retraction of the bolt, said last mentioned means being engageable with the first mentioned means to dog the same, and operable 75

by the second projection on the bolt to effect a release of said first mentioned means.

3. In a door latch, a case plate, a latch bolt having a shank movable over said case plate, a handle stem journaled in the case plate beside and terminating short of said shank, a rollback non-rotatably sleeved on the stem between the case plate and shank and engageable with a portion of the latter to effect a retraction of the bolt, and means holding the stem in the case plate so that the rollback will be retained on the stem, including means forming a guide for the bolt shank.

4. In a door latch, a case plate, a latch bolt having a shank movable over said case plate, a handle stem extending through the case plate toward but terminating short of said shank, a roll back non-rotatably sleeved on the stem between the case plate and shank and engageable with a portion of the latter to effect a retraction of the bolt, and means holding the handle stem in the case plate so that the roll back will be retained on the said stem, including means extending through the bolt shank.

5. In a door latch, a case plate, a latch bolt having a shank movable over said case plate, a handle stem extending through the case plate toward but terminating short of said shank, a roll back non-rotatably sleeved on the handle stem and engageable with the shank to effect a retraction of the bolt, and means maintaining the handle stem and roll back in assembled relation relative to the case plate and shank, including an element extending through the shank and secured to said handle stem.

6. In a door latch, a case plate, a latch bolt having a shank movable over said case plate, a handle stem extending through the case plate toward but terminating short of said shank, a roll back non-rotatably sleeved on the handle stem and engageable with the shank to effect a retraction of the bolt, and means holding the handle stem and roll back in assembled relation relative to the case plate and bolt shank including means forming a guide for the bolt shank.

7. In a door latch, a latch bolt having a shank, a roll back engageable with one portion of the shank to move the bolt, and a second roll back engageable with another portion of the shank to move the bolt, engageable with the first mentioned roll back to dog the same, and actuatable by the first mentioned portion of the shank to release the first mentioned roll back.

8. In a door latch, a latch bolt having a shank, a roll back engageable with one portion of the shank to move the bolt, and a second roll back engageable with another portion of the shank to move the bolt, engageable with the first mentioned roll back to dog the same, and actuatable by the last mentioned portion of the shank to release the first mentioned roll back.

9. In a door latch, a case plate attachable to a door, a latch bolt having a shank slidably over one side of said case plate and engageable with a keeper upon a jamb for the door, a handle stem upon the other side of said case plate, said latch bolt shank being movable relative to said handle stem upon pressure being exerted endwise of the bolt incident to closing the door against its jamb, a rollback for effecting a retraction of the bolt carried by the handle stem between the case plate and bolt shank and engageable with a portion

of the latter, and inaccessible means carried by the handle stem, forming a guide for the bolt shank and retaining the rollback between the bolt shank and case plate.

10. In a door latch, a case plate having a substantially flat portion, a latch bolt having a longitudinally movable shank upon one side of the flat portion of the case plate, a handle stem extending through the flat portion of the case plate toward but terminating short of said shank, said shank being movable relative to said stem and having a longitudinally extending slot therein in alignment with said stem, a rollback sleeved on said stem between the shank and flat portion of the case plate, and means maintaining the handle stem in assembled relation with the case plate and holding the handle stem against withdrawal from the rollback, including a member projecting from the handle stem within the slot aforesaid and forming a guide for the longitudinally movable bolt shank.

11. In a door latch, a case plate, a latch bolt having a longitudinally movable shank upon the inner side of the case plate, a handle stem operable from the outer side of the case plate extending through the case plate toward but terminating short of said shank, said shank being movable relative to the said stem and having a longitudinally extending slot in alignment with said stem, and means holding the handle stem in the case plate and forming a guide for the bolt shank, including an element extending through the longitudinally extending slot in the bolt shank and secured to the handle stem.

12. In a door latch, a slidable bolt shank having two lateral projections, means engageable with one of said projections to actuate said shank, and means operable independently of the means just mentioned having a portion engageable with the other projection to actuate said shank, having another portion engageable with the first mentioned means to dog the same, and having a third portion engageable by the first mentioned projection on said shank upon movement of the latter by pressure exerted endwise thereof to cause the second mentioned portion of said second mentioned means to be dis-engaged from the first mentioned means.

13. In a door latch, a slidable bolt shank having a lateral projection, means independent of said projection for sliding said shank, and actuating means for the bolt shank independent of the means just mentioned having portions straddling said projection, said shank being slidable relative to both of said means upon pressure being exerted endwise thereof, one of said portions being engageable with the first mentioned means upon movement of the second mentioned means in one direction to render the first mentioned means inoperative, and being engageable with said projection upon movement of the second mentioned means in another direction to slide said shank relative to said first mentioned means, the other of said portions being movable by said projection upon movement of the shank by pressure exerted endwise thereof when the first mentioned portion of the second mentioned means is in engagement with the first mentioned means to restore the said second mentioned means to normal position and thereby release the first mentioned means.

WILLIAM C. DEVEREAUX.
